DESIGN FOR A TRANSPORT AIRPLANE

Vincent J. Burnelli, New York, N. Y., assignor to
Burnelli Aircraft, Ltd., Dover, Del., a corpora-
tion of Delaware

Application February 23, 1933. Serial No. 47,290

Term of patent 14 years

To all whom it may concern:

Be it known that I, VINCENT J. BURNELLI, a citizen of the United States, residing at the borough of Manhattan, in the city, county and State of New York, have invented a new, original, and ornamental Design for Transport Airplanes, of which the following is a specification, reference being had to the accompanying drawings, forming part thereof.

Figure 1 is a plan view of a transport airplane, showing my new design.

Fig. 2 is a front elevation thereof.

Fig. 3 is a side elevation.

Fig. 4 is a side elevation partly in section on the line 4—4 of Fig. 1.

Figure 5 is a top perspective view of the airplane in flight, and

Figure 6 is a perspective view of the airplane in flight as seen from underneath.

I claim:

The ornamental design for a transport airplane, as shown.

VINCENT J. BURNELLI.
